UNITED STATES PATENT OFFICE

LOUIS J. KAPLAN, OF GREENWICH, OHIO, ASSIGNOR, BY MESNE ASSIGNMENTS, TO THE KITCHEN KATCH-ALL CORPORATION, OF GREENWICH, OHIO, A CORPORATION OF OHIO

KITCHEN UTENSIL

Application filed September 6, 1928. Serial No. 304,191.

The present invention relates, as indicated, to kitchen utensils, and more particularly to garbage pails of the type which are adapted to be swung under a sink. The primary object of the invention is to provide novel means for supporting the cover of such a container in its various desirable positions. Further objects will appear as the description proceeds. To the accomplishment of the foregoing and related ends, 10 said invention, then, consists of the means hereinafter fully described and particularly pointed out in the claims.

The annexed drawings and the following 15 description set forth in detail certain mechanism embodying the invention, such disclosed means constituting, however, but one of various mechanical forms in which the principle of the invention may be used.

20 In said annexed drawings:

Fig. 1 is a side elevation of a container constructed in accordance with the present invention; Fig. 2 is a top plan view thereof; Fig. 3 is a view similar to Fig. 2 with the 25 cover swung to open position; and Fig. 4 is a fragmental vertical section taken substantially upon the line 4—4 of Fig. 2.

Referring more particularly to the drawings, it will be seen that the reference 30 number 10 indicates generally a container to which is secured, by means of rivets 11, the central or base portion 12 of a bracket member later to be described. The upper edge of the container is rolled to form a bead 13 as shown.

A cover member 14 is formed with an 35 standing annular flange 15 the upper end of which is folded outwardly as at 16. Said flange 15 is adapted to fit within the 40 bead 13, while the folded portion 16 is adapted to rest upon the upper surface of the bead 13, whereby a suitably tight fit is provided between the container and its cover.

45 From the lower end of the base portion 12 of the bracket there extends a leg or projection 17 perforated as at 18 adjacent its outer end. At the upper end of the 50 section 12 said bracket is bent outwardly to form a second projection 19 substantially

parallel with the projection 17 and perforated adjacent its outer end as at 20. The bracket is bent upwardly as at 21 at the outer end of the projection 19, and then is rebent as at 22 to form a platform having 55 bifurcations 23 extending inwardly therefrom.

A pair of rivets 24 or other similar fastening means secure to said cover member 14 a foot 25 of a pivot member which is 60 bent upwardly at 26, laterally at 27, downwardly at 28, and which is then given a reverse bend as at 29 at a point immediately below the plane of the edge 16. The straight portion 30 of the pivot pin is adapted to pass through the apertures 20 and 18 whereby said cover 14 is swiveled to said bracket. 65

In use, the cover 14 is normally in the 70 position shown in Fig. 1, the relatively tight fit between the cover member 14 and the bead 13 preventing any material escape of odors from the container. If, now, it is desired to open the container, the knob 31 upon the cover member 14 is grasped and 75 the cover member is lifted slightly and swung about the pivot pin 30 to any desired position between that illustrated in Fig. 1 and that illustrated in Fig. 3. From an inspection of Fig. 4 it will be obvious that 80 the cover member cannot be swung out of register with the container top unless said cover member is lifted sufficiently to carry the shoulder 29 above the plane of the bifurcations 23. When the cover and pin are 85 so lifted and the cover is swung, the shoulder 29 engages the bifurcations 23 of the table 22 and holds the cover in such slightly elevated position. Thereafter, when it is 90 desired to close the container, the cover may be given a lateral push, and it will swing upon the pivot pin 30 until the shoulder 29 comes into register with the opening 95 between the bifurcations 23.

At this time, the cover member 14 is in registry with the container 10 and, as the shoulder 29 drops between the bifurcations 23, further swinging movement of the cover is immediately arrested and the whole mem- 100

ber drops down into the position shown in Fig. 4.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In combination with a receptacle open at its top, a cover therefor, a stud attached to said cover and having a downwardly directed end, a cam formed on said stud, and a bracket secured to said receptacle and adapted to receive said end, said bracket comprising a laterally extending portion perforated adjacent its outer end, an upwardly extending portion, and an inwardly extending portion, said last-named portion being bifurcated, and said stud end being received between the furcations of said last-named portion and in the perforation of said first-named portion.

2. In combination with a receptacle open at its top, a cover therefor, a stud attached to said cover and having a downwardly directed end, a cam formed on said stud, and a bracket secured to said receptacle and adapted to receive said end, said bracket comprising a laterally extending portion perforated adjacent its outer end, an upwardly extending portion, and an inwardly extending portion, said last-named portion being bifurcated, and said stud end being received in the perforation of said first-named portion, and said cam being received between the furcations of said last-named portion.

3. In combination with a receptacle, a bracket secured to said receptacle and comprising an outwardly extending portion formed with a perforation adjacent its outer end, an integral upwardly extending portion projecting from said outer end, and an integral inwardly extending portion projecting from the upper end of said second-named portion, said inwardly extending portion being formed with a slot at its inner end in vertical alignment with said perforation, a cover for said receptacle, a stud secured to said cover and having a downturned leg and a cam formed in said leg, said leg being received in said perforation, and said cam being adapted, in one position of said cover, to be received in said slot, and in all other positions of said cover to ride on the walls defining said slot.

60 Signed by me this first day of September, 1928.

LOUIS J. KAPLAN.
